UNITED STATES PATENT OFFICE.

JASON C. STEARNS, OF WORCESTER, MASSACHUSETTS.

ELECTRIC-LAMP SOCKET AND CONNECTOR.

1,115,874.

Specification of Letters Patent.

Patented Nov. 3, 1914.

Application filed March 23, 1912. Serial No. 685,709.

To all whom it may concern:

Be it known that I, JASON C. STEARNS, a citizen of the United States, residing at Worcester, in the county of Worcester and State of Massachusetts, have invented a new and useful Electric-Lamp Socket and Connector, of which the following is a specification.

This invention relates to a socket particularly adapted for electric lamps, and especially for that type of lamps which are of small size, known as the "Edi-Swan" lamp, and used principally on automobiles, but it is capable of being used either in the same or slightly modified forms for other kinds of lamps and for other electrical purposes both as a socket and connector.

The principal objects of the invention are to provide a much simplified form of socket and connector of such a character that it can be made mainly of a single tube of sheet metal, with means therein for holding the connections in a fixed position so as to avoid the necessity of shoulders to prevent longitudinal and lateral motion of the terminals. Also to provide certain improvements in features of construction as will appear hereinafter.

Reference is to be had to the accompanying drawings in which—

Figure 1 is a side elevation of an Edi-Swan lamp socket and connector constructed in accordance with this invention. Fig. 2 is a similar view with parts shown in central sectional view, and Fig. 3 is a view similar to Fig. 1 with the parts of the device removed from the tube and shown separately.

The lamp socket is shown as particularly adapted for use with an Edi-Swan lamp having the usual metallic armor 11 on the neck thereof and provided with opposite locating pins 12 and also with two metallic terminals 13 located in the same plane and separated by an insulating body on which the armor 11 is placed. For the purpose of holding this lamp a cylindrical metallic casing 15 is shown having opposite bayonet slots 16 constituting with the pins 12 a bayonet joint for the lamp. Inside the casing 15 is located an insulating block 18 formed of hard rubber or any other insulating material and provided with a pair of cylinders 19 extending substantially therethrough, each having a plunger 20 at one end and an opposite plunger 21 at the other end held

apart by springs 22 confined in the tube. For the purpose of holding this block in proper position within the casing and constituting a means of limiting the longitudinal and transverse motion of the lamp, the block is provided with a headed screw 23 adapted to be locked in the elongation 24 of one of the bayonet slots 16. This elongation is so located that it brings the terminals 21 into proper position to be engaged by the terminals 13 when the parts are locked in their several positions, as indicated in Fig. 1. At the opposite end of the casing 15 it is provided with another insulating plug 30 having a pair of conducting members 31 extending therethrough and adapted to receive conductors 32 from any desired point. These parts 31 form metallic contacts at the end of the block 30 for connection with the plungers 20. This block is held in the end of the casing by a bayonet joint 33, as will be readily understood, in such positions that the ends of the conductors 31 are in contact with the plungers 20.

From this it will be seen that the device is reduced to very simple terms, and particularly is arranged in cylindrical form, so that it can be applied in a bored hole in a wall or the like. The parts are very simple and the application of the plug 30 at one end and the lamp at the other results in providing an absolutely efficient electrical connection where the spring-pressed plungers come against the metallic terminal surfaces, and the same springs furnish a means for holding both end pieces by their respective bayonet joints. Yet, this means being yielding, the lamp or plug can be removed very simply by first pressing it in and then turning it. It will be observed also that in place of the lamp, another plug similar to 30 can be used which will convert the device into a connector. The central insulating block 18 and the way in which it is held in position are particularly important, because they furnish an extremely simple way of forming this connection between the lamp and plug 30 without the provision of any shoulder or other mechanism inside the casing for limiting the turning or longitudinal motion thereof.

Although I have illustrated and described a preferred embodiment of the invention, I am aware that many modifications can be made therein by any person skilled in the art without departing from the scope of the

invention as expressed in the claims. Therefore I do not wish to be limited to all the details herein shown and described or to the particular use of the device indicated, but

5. What I do claim is:

1. In an electrical connector or socket, the combination of a casing having slots at its opposite ends, and provided with a longitudinal slot extending from one of said slots 10 toward the center, a screw in said extending slot, a central plug adapted to be held in adjusted positions in the casing by said screw and provided with terminals, and a pair of members extending into the ends of 15 the casing and held by the slots in fixed position and having terminals which when in that position come into engagement with the first named terminals.
2. In an electrical connector or socket, the 20 combination of a cylindrical casing having bayonet joint slots at its opposite ends, and provided with a longitudinal slot extending

from one of said bayonet slots toward the center, a screw in said extending slot, a central plug adapted to be held in adjusted positions in the casing by said screw and provided with two pairs of opposite plungers 25 resiliently pressed outwardly toward the opposite ends of said casing, each plunger being electrically connected with one of the 30 opposite plungers, and a pair of members extending into the end of the casing and held by the bayonet slots in fixed position and having terminals which when in that 35 position come into engagement with the plungers.

In testimony whereof I have hereunto set my hand, in the presence of two subscribing witnesses.

JASON C. STEARNS.
